Howard E. Thompson
ATTORNEY

UNITED STATES PATENT OFFICE.

EMRY DAVIS, OF NEW YORK, N. Y.

AUTOMATIC INKWELL.

Application filed July 13, 1925. Serial No. 43,144.

To all whom it may concern:

Be it known that I, EMRY DAVIS, a citizen of the United States, and residing at New York, in the county of New York and State of New York, have invented certain new and useful Improvements in Automatic Ink-wells, of which the following is a specification, such as will enable those skilled in the art to which it appertains to make and use 10 the same.

This invention relates to inkwells or stands which are automatic in operation or which are so constructed as to provide for the automatic feeding of ink to a pen point insertable thereinto, and the object of the invention is to provide a device of the class specified the ink feeding plunger of which normally projects into a recess in the head or top portion of the device and yet is retained in position below the top face of said head whereby the angular insertion of a pen into the inkwell is facilitated, and whereby ink may be fed to the pen point when the pen is in such angular position without inconvenience to the operator; a still further object being to provide an ink feed control valve or nozzle which by reason of its construction will prevent sudden discharge of the ink through the feed device and yet provide for an even and positive feed of ink to a pen point of a pen inserted thereinto; a further object being to provide improved means for feeding ink from the well to said control device whereby the feed of ink is positive at all times, said ink feed control device also functioning as a seal for closing the end of the feed tube which opens into the well proper; and with these and other objects in view the invention consists in a device of the class and for the purpose specified which is simple in construction and operation and efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a transverse sectional view through an inkwell made according to my invention and illustrating the method of its use;

Fig. 2 is a section on the line 2—2 of Fig. 1;

Fig. 3 is a perspective detail view of an ink feed and control device which I employ;

Fig. 4 is a view similar to Fig. 1 but showing only a part of the construction on an enlarged scale and illustrating a modification; and,

Fig. 5 a section on the line 5—5 of Fig. 4.

In carrying my invention into effect, I provide a well 10 of any conventional shape or form and preferably composed of glass, the top being provided with an opening 11 in which is fitted a sleeve-like cap 12 between which and the walls of the opening 11 is a suitable packing 13 to render the connection of the cap 12 with the well 10 airtight. Frictionally retained and detachably mounted in the cap 12 is a sleeve 14, the upper end of which is flared outwardly as seen at 15 and is provided with a convex recess 16 in its upper face, the other end portion 17 of said sleeve projects into the chamber 18 of the well 10 to a predetermined point adjacent the bottom thereof, which point controls the required height of the ink to be maintained in the well for discharge therefrom in the use of the device.

The above described construction is old in the art and is illustrated for showing one method of carrying my present invention into effect, and it will be noted that a vent passage 19 opens into the bore of the sleeve 14 and also into the chamber 18. Movable mounted within the bore of the sleeve 14 is an ink feeding plunger 20 in the form of an elongated tubular body having a cross head 21 at its upper end from which extends a depending tube 22 within which is formed the ink feeding bore 23 of the device, the tube 22 is contained centrally within the tube of plunger 20 and a chamber 24 is formed around the tube 22 in which is mounted a light coil spring 25 which normally sits upon the cross head of a tubular member 26, the depending walls of which are provided with slots 27 on oppositely disposed faces to permit the free passage of tubular pins 28 therethrough, the pins 28 being mounted in the tubular plunger 20 and the tube 22 thereof as clearly seen in Fig. 1 of the drawing.

It will be noted that the bores of the tubular pins 28 open into the chamber 18 of the wall and also into the bore 23 of the tube 22, and an ink feed control member 29 is mounted in the lower end portion of the bore

23, the head 30 of said device fitting snugly in said bore to seal the lower end thereof, while the upper or inner end of said member is fashioned to form spiral grooves 31, 5 which grooves are formed by spirally arranged blades or fins 32, and the reduced shank portion 33 of the member 29 is positioned within the bore 23 in line with the tubular pins 28 to provide for the feeding 10 of ink upwardly through the bore 23 as will be apparent.

The spring 25 normally operates to project the cross head 21 of the tubular ink feed member 20 above the bore of the sleeve 14 15 and the top of said member 20 is within the recess 16 and does not project above the top of the flared head 15 as seen in dotted lines in Fig. 1 of the drawing. Upon the insertion of the pen or pen point into the bore 20 23 in the plunger 20 and moving said plunger 20 downwardly, the ink is forced upwardly through the bore 23 by the action of said plunger member 20 and the ink is supplied to the pen as seen in Fig. 1 of the drawing, 25 and it will also be apparent that by reason of the projection of the plunger 20 a pen may be inserted angularly into said plunger without engaging the flared head 15 as indicated in dotted lines in Fig. 1 of the drawing, 30 and without in any way affecting the operation of supplying ink to the pen which result has been experienced with other devices of the class under consideration. It will also be apparent that by virtue of the 35 spiral grooves 31 in the ink feed and control member 29, the sudden inertia of the ink upwardly through the bore 33 in a sudden pressure of the plunger 20 is obviated or checked and a constant or steady feed or supply of ink is provided. It will also be apparent that the plunger 20 may be depressed to a greater degree than the depression shown in full lines in Fig. 1 of the drawing, 40 and that part of the ink which passes upwardly around the member 20 and within the bore of the sleeve 12 and which may overflow over the top of the member 20 in the upward or return of the member 20 to normal position, will either pass down through the 45 vent 19 or through the passage provided between said member by reason of the vent employed.

Instead of providing the tubular pins 28 as shown in Figs. 1 and 2 of the drawing, I 50 may provide a single tubular pin 34 as seen in Figs. 4 and 5 of the drawing, and with this construction it is preferred that the lower end of the tube 22 be enlarged as seen at 35 and the diameter of the tubular pin 34 will be greater than that of the pins 28, and centrally of the pin 34 will be formed an aperture or passage 36 through which the member 29 is free to pass, the port 36 being of the same diameter as the diameter of the 60 bore 23 and the head 30 of the member 29

will extend into the bore 36 to retain the pin 34 against displacement. With this construction it will be apparent that the ink will pass into and through the bore of the pin 34 around the stem 33 of the member 29 and up through the grooves 31 and into the bore 23, the lower end of the bore 23 being closed by the head 30 as in the construction shown in Figs. 1 and 2.

In both forms of construction shown the pins 28 and the pin 34 project beyond the outer walls of the member 20 and form stops for limiting the upward movement of said member by engagement with the lower or inner end portion of the sleeve 14, as will be 80 apparent on a consideration of Fig. 1 of the drawing.

Heretofore it has been a difficulty in the use of ink-wells of the class under consideration and especially in cleaning out such wells 85 for their further use in properly positioning the feed tubes and other feeding means for controlling the supply of ink to the depending plunger or the bore of such plunger and such devices have not been fool-proof. With the present construction, however, the assemblage or disassemblage of the parts and their re-assemblage must always result in the successful operation of the device, the pins 28 engaging the head 29 as seen in Fig. 90 1 of the drawing to limit their inward movement, the member 29 being removed by a pin or rod passed downwardly through the bore 23 and as in Figs. 4 and 5 of the drawing the member 29 must pass through the 100 bore 36 and the head 30 of the member 29 positively fixes the position of the pin 34, and by virtue of these improvements as well as the method of constructing, mounting and operating the member 20 results in a more 105 practical, fool-proof and positively functioning inkwell of the automatic type.

It will be understood that while I have shown certain details of construction for carrying my invention into effect, that I 110 am not necessarily limited to these details and various changes therein and modifications thereof may be made, within the scope of the appended claims, without departing from the spirit of my invention or sacrificing its advantages.

It will be apparent that in the operation of the device the ink flow is controlled and regulated primarily by the arrangement of the spiral grooves 31 in the member 29 and 120 the pitch arrangement of these grooves to deflect the ink onto the walls of the bore 23 to cause such baffling and friction of the ink flow as to prevent its sudden or fountain-like discharge but providing a quick but 125 steady feed of the ink upwardly through said bore, and this feature together with the specific mounting of the member 21 in the tubes 28 and 34 as well as the normal position assumed by the upper end of the plunger 130

20 constitutes the distinctive features of my invention.

Having fully described my invention, what I claim as new and desire to secure by Letters Patent, is:—

1. An automatic inkwell of the class described comprising a well body, a closure for said body, a tubular member detachably mounted in connection with said closure and frictionally retained in position, the upper end of said tubular member being provided with a recess, an ink feeding plunger movably disposed in said tubular member and the upper end portion of which normally projects into said recess at a point slightly below the top of said tubular member, means detachably mounted in connection with the lower end portion of said ink feeding plunger for controlling the feed of ink therinto and therethrough, said means being in fixed position, tensional means for normally holding the plunger in a raised position, and means independent of said first named means for controlling the passage of ink from the chamber of the well to said first named means and said plunger.

2. In an automatic inkwell of the class described, the combination with the movable ink feeding plunger thereof, of an ink feed control device detachably mounted in connection with said plunger, said device comprising a pin-like body one end of which is provided with an enlarged head and the other end of which is provided with spirally arranged grooves.

3. In an automatic inkwell of the class described, the combination with a movable ink feeding plunger thereof, of a tubular member transversing the feed bore of said plunger and an ink feed control device mounted in said feed bore and transversing said tube.

4. In an automatic inkwell of the class described, the combination with a movable ink feeding plunger thereof, of a tubular member transversing the feed bore of said plunger and an ink feed control device mounted in said feed bore and transversing said tube, said device serving to retain said tube in fixed position within said plunger.

5. In an automatic inkwell of the class described, the combination with a movable ink feeding plunger thereof, of a tubular member transversing the feed bore of said plunger and an ink feed control device mounted in said feed bore and transversing said tube, said device serving to retain said

tube in fixed position within said plunger, and controlling the supply of ink to said device.

6. In an automatic inkwell of the class described, the combination with a movable ink feeding plunger thereof, of a tubular member transversing the feed bore of said plunger and an ink feed control device mounted in said feed bore and transversing said tube, said device serving to retain said tube in fixed position within said plunger, and controlling the supply of ink to said plunger having spirally arranged feed grooves for directing the ink feed through said plunger or the feed bore thereof against the walls of said bore.

7. In an automatic inkwell of the class described, an ink feeding plunger having a feed tube, a plug for closing the end of said tube, said plug having within said tube a reduced portion and spirally arranged feed grooves, and means comprising a tube mounted in connection with said plunger and opening into said feed tube adjacent the reduced portion of said plug whereby ink may be fed into said feed tube through said grooves.

8. In an automatic inkwell of the class described, an ink feeding plunger having a feed tube, and means detachably mounted in the lower end portion of the bore of said tube for controlling and regulating the feeding of ink thereinto, said means being in fixed position in said tube.

9. In an automatic inkwell of the class described, an ink feeding plunger having a feed tube, and means detachably mounted in the lower end portion of the bore only of said tube for controlling and regulating the feeding of ink thereinto and for closing the lower end portion of said tube, said means being in fixed position in said tube.

10. In an automatic inkwell of the class described, an ink feeding plunger having a feed tube, means detachably mounted in the lower end portion of the bore only of said tube for controlling and regulating the feeding of ink thereinto and for closing the lower end portion of said tube, said means being in fixed position in said tube, and means associated with said tube and said first named means for directing ink from the well to said means and said tube.

In testimony that I claim the foregoing as my invention I have signed my name this 10th day of July 1925.

EMRY DAVIS.
